UNITED STATES PATENT OFFICE.

GROSVENOR ATTERBURY, OF NEW YORK, N. Y.

LIFTING DEVICE FOR HOLLOW BLOCKS.

1,171,580.

Specification of Letters Patent. Patented Feb. 15, 1916.

Application filed March 31, 1910. Serial No. 552,487.

To all whom it may concern:

Be it known that I, GROSVENOR ATTERBURY, a citizen of the United States, residing in the city, county, and State of New York, have invented certain new and useful Improvements in Lifting Devices for Hollow Blocks, of which the following is a full and complete disclosure.

My invention relates particularly to lifting devices for blocks made of cement or cementitious material, of large size, and the object of my invention is to produce a device which, while being simple and not liable to get out of order, will engage and lift hollow blocks without damaging the blocks, even though the blocks be not thoroughly set or hardened, and which will be to a large extent automatic in operation and require but little attention from the operator, and operate entirely in the interior of the block so as to facilitate its placing on or lifting from a flat surface or between adjoining sections or blocks.

In the drawing accompanying and forming a part of this specification, I have illustrated two forms or modifications of my invention.

In this drawing Figure 1 is a side elevation of the preferred form of my invention shown in position in a hollow block, the latter and a portion of the lifting device being in section. Fig. 2 is a side elevation of the lower portion of the lifting device shown in Fig. 1. Fig. 3 is a sectional view taken on the line 3—3 of Fig. 2. Fig. 4 is a plan view of the centering device shown in Fig. 1. Fig. 5 is a side elevation of a modified lifting device with the block and centering piece in section. Fig. 6 is a side elevation showing two lifting devices, as shown in Fig. 5, arranged to simultaneously lift two hollow blocks or one large block with two hollow spaces. The blocks and portions of the lifting mechanism are shown in section.

Referring in detail to the modification shown in Figs. 1, 2, 3 and 4, the numeral 1 designates a block to be lifted, which is hollow, and has oppositely disposed recesses 2 cast in its interior walls at the bottom. The lifting device comprises side members 3,

joined at their upper ends by a pivot 4, and connecting at their lower ends with the slides 5 and 6. These members 5 and 6 are of substantial width, and in connection with the member 7, with which they have a sliding engagement, form a base for the lifting device, adapted to support it in an upright position. The links 31 serve to connect the intermediate portions of the members 3 with the lower end of the member 32. To the upper end of the latter there is attached the lifting chain 8, terminating at its upper end in the lifting ring 9. The chain 10 which is connected to the members 3 at their upper end by the pivot pin 4, is for use in lowering the device into the block. When the lifting device is lifted through the chain 8, the first result is to pull up the links 31 and thrust the side members carrying the slides 5 and 6 outwardly, so that they will enter the recesses in the lower end of the block and act as supports for the same. When the chain 10 is in use for lowering the device into a block, the force of gravity acting through the side members 3, and especially through the member 32, closes the device so that it may be lowered into the block or withdrawn therefrom. Attached to the side members 3 are spring guides 3^a which aid in centering the lifting device particularly while it is being expanded, and in keeping it closed while it is being inserted or withdrawn. A centering or finding device comprising a top plate 11 and guides 12 is arranged to slide on the lifting chain 8. The object of this centering device is to automatically center the lower end of the lifting device when it is lowered into a block, so that the members 5 and 6 will register with the recesses 2, and by centering the chain in the interior of the block to keep the block steady and in a vertical position while suspended. In order that this centering device may be used with blocks having openings of different sizes, the members 12 are made adjustable by shifting the bolts 13 in the radially spaced holes 33.

In the modification shown in Fig. 5, the side members 14 of the lifting device are pivoted to the member 15 by pins 16, and are connected at their upper ends by the

links 17. These links are connected at their inner ends by the pin 18, adapted to slide vertically in the slot 19. A lowering chain 20 is provided, attached at its lower end to 5 the upper portion of the member 15. Attached to member 15 are the spring guides 15^a which perform the same function as the corresponding guides 3^a in the modification shown in Fig. 1. These guides are 10 more useful in this particular apparatus as the hooks 22 are more likely to engage accidental roughnesses upon the interior of the block. There is also a lifting chain 21 attached at its lower end to the pin 18. There 15 is also provided a centering device the same as that described in connection with Fig. 1. With this arrangement, when the device is being lowered into the block by means of chain 20, the force of gravity will cause the 20 members 14 to hang vertically, so that they pass readily into the block, but when the device has been lowered and the block is ready to be lifted, and the pull is on the chain 21, the lower ends of the side members 14 are thrust outwardly by the pull 25 on the links 17, and the hooks 22 are forced into the recesses 2, and firmly engage the block.

In Fig. 6, where the device of Fig. 5 is 30 shown in duplicate applied to lift two blocks at the same time, or one large block having two recesses, there is provided a spacing member 24 adapted to hold the lifting devices at a predetermined distance from each 35 other. This spacing member is made in two parts connected by bolts, and its length may be adjusted by shifting the bolts into the holes 26. This double lifting device is also useful where blocks are cast with a 40 plurality of hollow spaces.

The lifting device shown in Fig. 5 is 45 adjustable to operate with openings of different size, by shifting the pins 16 to the holes 27, and by shifting the pin 18 to the 50 holes 29, or by making either of these changes. The operation of my improved lifting device is obvious from the foregoing description. In the case of that form shown in Fig. 1 the operator attaches the 55 lifting hook 30 to the ring 9^a at the upper end of the lowering chain and the device is readily lowered into the block. The ring 9^a is then disengaged and the ring 9 engaged, and a pull on the lifting chain 8 60 opens the side members 3 and forces the slides 5 and 6 into the recesses 2. The block is then lifted to its desired position and the ring 9 is disengaged and the ring 9^a engaged so that the lifting device may be 65 withdrawn from the block. The same is true of the modification shown in Fig. 6, except that the hooks 23 and 23^a take the place of the rings 9 and 9^a, and are used alternately in the same manner, according

to whether the device is being lowered into 65 the block or is intended to engage and lift the block.

In the apparatus shown in Fig. 5 the change from lowering chain to lifting chain is accomplished by means of rod 24. At 70 each end of rod 24 there are formed hooks 25 and 25^a so that the change from one chain to the other may be made by sliding rod 24 over the lifting hook 30, thus relieving the operator of the weight of the 75 chains while making the change.

While I have described only two modifications of my invention, I am aware that numerous other modifications may be made by those skilled in the art without departing from the spirit of my invention, and I wish to secure protection for all such modifications as come within the scope of my claims.

What I claim is:

1. A lifting device adapted for use with a hollow block, having oppositely-disposed recesses near its lower end, comprising pivoted members, lowering means adapted to maintain the lifting device in a closed position, lifting means adapted to open said pivoted members and cause them to enter the recesses of said block, centering devices secured to said lifting means and a centering and finding device for said lifting means independent thereof and adapted to engage the upper end of the block substantially as described.

2. In combination with a lifting device adapted for use with a hollow block having oppositely-disposed recesses near its lower end, said lifting device being adapted to enter said recesses of said block, a finding device independent of the lifting device and adapted to engage the upper end of the block to thereby center the lifting device in the block and steady the block during the lifting operation.

3. In combination with a lifting device adapted for use with a hollow block having oppositely disposed recesses near its lower end, a centering and finding device independent of the lifting device and adapted to guide said lifting device while being lowered into said hollow block and to steady the block during the lifting operation.

4. In combination with a lifting device, adapted for use with a hollow block, having oppositely disposed recesses near its lower end, a centering and finding device independent of the lifting device and comprising a top plate and guides so arranged as to automatically center the said lifting device when it is lowered into the blocks so that the lifting device will register with the recesses and to automatically steady the block during the lifting operation.

5. In combination with a lifting device

adapted for use with a hollow block having oppositely-disposed recesses near its lower end, a centering and finding device independent of the lifting device and adapted to guide and control the same comprising a top plate and guides, the said guides being adjustable in radial recesses in said

top plate, whereby said centering device may be used with blocks having openings of different sizes.

GROSVENOR ATTERBURY.
